UNITED STATES PATENT OFFICE.

CHARLES WHITELEY, OF NEWARK, NEW JERSEY.

ORNAMENTAL ARTICLE OF MANUFACTURE, AS HAT-PIN, BUTTON, BROOCH, AND THE LIKE.

1,191,636.

Specification of Letters Patent. Patented July 18, 1916.

Application filed January 27, 1916. Serial No. 74,550.

To all whom it may concern:

Be it known that I, CHARLES WHITELEY, a citizen of the United States, residing at Newark, in the county of Essex and State 5 of New Jersey, have invented certain new and useful Improvements in Ornamental Articles of Manufacture, as Hat-Pins, Buttons, Brooches, and the like; and I do hereby declare the following to be a full, clear, 10 and exact description of the invention, such as will enable others skilled in the art to which it appertains to make and use the same, reference being had to the accompanying drawings, and to characters of reference 15 marked thereon; which form a part of this specification.

The present invention has reference, generally, to improvements in the construction of ornamental hat-pins, buttons, brooches 20 and similar articles of personal wear; and, the invention relates, more particularly, to a novel construction of device of the character above mentioned adapted to provide a very durable, strong, cheaply produced and 25 yet artistically ornamented article.

The present invention has for its principal object to provide a novel construction of an article of personal wear, such as a hat-pin, button, brooch or similar article, the same 30 being provided on its face with an ornamental element, such as an enameled ornament, jewel or similar element, together with a novel construction of means for mounting and retaining such ornamental element in 35 proper relation to the article with which it is used; such means for mounting and retaining said ornamental element being of such character as to be easily associated with the ornamental element without danger of 40 injuring or marring the same.

Other objects of the present invention, not at this time more particularly enumerated, will be clearly understood from the following detailed description of the present invention. 45

With the various objects of my present invention in view, the same consists, primarily, in the novel construction of ornamental hat-pin, button, brooch or the like hereinafter 50 set forth; and the invention consists, furthermore, in the novel arrangements and combinations of the various devices and parts, as well as in the details of the construction of the said parts, all of which will 55 be more fully described in the following

specification, and then finally embodied in the claims which are appended to and which form an essential part of the said specification.

The invention is clearly illustrated in the 60 accompanying drawings, in which:—

Figure 1 is a side elevation of a hat-pin made according to and embodying the principles of my present invention; and Fig. 2 is a top view of the same. Fig. 3 is a collective vertical section of the various detail parts making up the construction of 65 said novel hat-pin, and illustrating their relation to each other in performing the assembling of the same to make up the completed device. Fig. 4 is a vertical section of 70 the said hat-pin showing the parts thereof assembled and the completion of the first operation of curling over the bead for providing the holding means for the ornamental 75 element, and the said ornamental element in place ready to be engaged by the holding means to be formed in said bead. Fig. 5 is a similar vertical section of the hat-pin completed, and showing the completed formation in said bead of the holding means for 80 engaging and retaining the ornamental element, said section being taken on line 5—5 in said Fig. 2. Fig. 6 is a horizontal section of said hat-pin, taken on line 6—6 in 85 said Fig. 5, looking in the direction of the arrow α . Fig. 7 is a vertical section of a button, brooch or the like, made according to and embodying the principles of my present invention. Fig. 8 is a top view of an 90 incompletely hat-pin, button, brooch or the like, showing a modification of my present invention. Fig. 9 is a similar top view of the same with a retaining bead formed to engage and retain an ornamental element in 95 place.

Similar characters of reference are employed in all of the hereinabove described views, to indicate corresponding parts.

Referring now to Figs. 1 to 6 inclusive 100 of the accompanying drawings, the reference character 1 indicates a complete hat-pin made according to and embodying the principles of my present invention, the same comprising a hollow head-shell 2 open at 105 its upper end, and preferably provided with an inverted conical bottom portion 3, provided at its apex with an opening through which is inserted a pin-shank 4. At the juncture of said bottom portion 3 with the 110

main body of said head-shell 2, and in the interior thereof, is formed an annular shoulder 5.

The reference character 6 indicates an anchor-disk, preferably of concavo-convex form, but having a flat central portion 7. This anchor-disk 6 is provided with a centrally disposed perforation or opening 8 through which is passed said pin-shank 4. 10 The inner or upper end of said pin-shank 4 is provided with a flattened horizontal arm or projection 9 extending at right angles thereto. The pointed or sharpened outer or lower end 10 of said pin-shank 4 is inserted 15 through said perforation or opening 8, and the pin-shank is passed through the latter until the said arm or projection 9 is brought up against the upper side of the flattened central portion 7 of the anchor-disk 6. The 20 pin-shank 4 is then passed through said head-shell 2 and the anchor-disk 6 is inserted within the latter so that its periphery is seated upon said annular shoulder 5. A finishing-sleeve or block 11, of any desirable ornamental contour, is slid upward upon said pin-shank 4 until it abuts against the apex of said conical bottom portion 3 of said head-shell 2, being firmly secured in such 25 relation, by being pinched upon said pin-shank, or soldered thereto, or affixed in any other suitable manner.

The reference character 12 indicates a lock-disk, also preferably of concavo-convex form, but having a flat central portion 13. 30 This lock-disk 12 is inserted within the upper open end of said head-shell 2 until its flat central portion 13 engages and rests upon said arm or projection 9 of said pin-shank 4, so that said arm or projection 9 is 35 securely and immovably held between said anchor disk 6 and said lock-disk 12. After the above described parts have been thus assembled, the upper marginal edge of said head-shell 2 is curled inwardly to form a 40 tubular bead 14, which extends over the marginal edges of said lock-disk 12 and thus securely holds the parts thus assembled in the relations above described. It will be apparent that the pin-shank 4 is thus securely 45 and immovably related to the head-shell 2, so as to be free from any loosening or longitudinal movement or yielding when the hat-pin is in use. The anchor-plate 6 prevents the said pin-shank from pulling out of or 50 away from the head-shell 2, and the lock-disk holds the pin-shank against yielding when thrusting the same through a hat while using the hat-pin.

The reference character 15 indicates an 55 ornament shell, or element preferably made of thin metal in which the desired ornamental characteristics are embossed. The said ornament shell 15 is enameled in desirable colors suitable to the character and kind 60 of ornamental design desired, the coating of

enamel 16 being baked or otherwise hardened upon the same. The marginal edges of said ornament element or shell 15 are sprung past the bead 14 so that said ornament element or shell seats itself upon the upper surface of said lock-disk 12. The bead 14, however, is but loosely related to the ornament element or shell and does not firmly embrace the same. In order to provide a proper retaining or holding means for said ornament element or shell 15, the said bead 14 is provided with a series of radiating transverse depressed grooves 17, preferably spaced equally one from the other, and extending around the entire bead 14. These depressed grooves 17 are formed by means of a suitable die after the ornament element or shell 15 has been assembled with the head-shell 2, and the formation of said depressed grooves 17 flattens down the bead 14 at intervals, thereby crowding out portions of the metal of the bead 14 into the form of holding or gripping projections 18, which extend inwardly from the inner circumference of said bead so as to engage the marginal sides or edges of said ornament element or shell 15, and thus serve to securely hold and retain the same in proper assembled or mounted relation to the head-shell 2 of the hat-pin, (all of which is more particularly illustrated in Figs. 2 and 5 of the accompanying drawings). The great advantage of such a construction is that said holding or gripping projections 18 may be formed out of a curled bead after the ornament element or shell 15 is in position, and forced into proper contact with the latter without danger of cracking, chipping or otherwise marring the more or less brittle enamel coating 16 of said ornament element or shell 15 to the detriment of the finished article and at the same time said holding or gripping projections may be thus easily and quickly produced, and at once formed and positioned operatively by a single operation, out of the metal of the head-shell 2, thus avoiding the necessity of extra parts and the assembling of such extra parts in the article.

Referring now to Fig. 7 of the drawings, I have illustrated therein a slightly modified construction of article, in the form of a button or brooch, which embodies, however, the principles of my present invention. In this view the reference character 19 indicates the body shell or backing of a button or brooch, the marginal edges 20 of which are turned upwardly and then formed or curled inwardly to provide a bead 14. Arranged within said body-shell or backing 19 is a stiffening plate 21, somewhat similar to the lock-disk 12 of the previously described construction. The reference character 15 indicates the ornament element or shell provided with the enamel coating 16, the same being laid within the bead 14 and supported 130

upon said stiffening plate 21. Said bead 14 is provided with a plurality of spaced transverse and radiating depressed grooves 17, which when formed therein force out the inner side of from the bead 14 the gripping or holding projections 18, the latter being adapted to engage and secure in place said ornament element or shell 15.

Referring now to Figs. 8 and 9 of the accompanying drawings, I have illustrated another slight modification of the construction of my present invention, as the same may be applied to hat-pins, buttons, brooches or similar articles. In this construction I provide the head or body shell having the upwardly extending marginal flange 22, and seated in this shell within the flange is the lock-disk or stiffening disk 23. I also employ the ornament element or shell 15 provided with the enameled coating 16, but I additionally provide, in connection with said ornament element or shell 15, a plurality of horizontally extending lugs or tongues 24 extending outwardly from the periphery of said ornament element or shell. In this construction the ornament element or shell 15 is placed in position before curling over the edge of the flange 22, so that when such curling takes place the bead 14 formed thereby is curled over and down upon said lugs or tongues 24, thus securely anchoring the ornament element or shell in place.

It will of course be understood that I do not limit myself to the use of the enameled ornament element above described, since it will be apparent that any other character or kind of ornament, such as a jewel, ivory, glass, bone, or in fact any other style of ornament regardless of the kind of material forming the same or the nature of its ornamentation or anesthetic appeal may be used.

I am aware that some changes may be made in the arrangements and combinations of the various devices and parts, as well as in the details of the construction of the said devices and parts, without departing from the scope of the invention as set forth in the foregoing specification, and as defined in the claims appended to and which form an essential part of the said specification. Hence, I do not limit my present invention to the exact arrangements and combinations of the several devices and parts as described in the said specification, nor do I confine myself to the exact details of the construction of the said parts as illustrated in the accompanying drawings.

I claim:—

1. In an article of the kind described, a shell, an ornament element seated within said shell, said shell having an upwardly extending marginal flange curled over and inwardly to form a tubular bead, said bead being provided with a series of spaced trans-

verse and radially disposed depressed grooves, and inwardly extending gripping projections forced from said bead at the inner ends of said depressed grooves for engaging and securing said ornament element 70 in place.

2. In an article of the kind described, a main shell, an ornament element, a disk seated within said shell, said ornament being supported upon said disk, said shell having an upwardly extending marginal flange curled over and inwardly to form a tubular bead adapted to engage and retain said disk within said shell, said bead being provided with a series of spaced transverse and radially 80 disposed depressed grooves, and inwardly extending gripping projections forced out from said bead at the inner ends of said depressed grooves for engaging the marginal edges of said ornament element to secure 85 the same in place.

3. In an article of the kind described, a head-shell closed at its bottom end and provided with a central perforation, an anchor-disk seated within said head-shell, said anchor-disk having a central perforation, a pin-shank extending downwardly through said perforations of said anchor-disk and the bottom of said head-shell, a laterally extending arm connected with the upper end 95 of said pin-shank and resting upon said anchor-disk, a lock-disk seated within said head-shell and resting upon said laterally extending arm of said pin-shank, an ornament element seated within said head-shell 100 and resting upon said lock-disk, and means connected with said head-shell for retaining said ornament element in place.

4. In an article of the kind described, a head-shell closed at its bottom end and provided with a central perforation, an anchor-disk seated within said head-shell, said anchor-disk having a central perforation, a pin-shank extending downwardly through said perforations of said anchor-disk and the bottom of said head-shell, a laterally extending arm connected with the upper end 110 of said pin-shank and resting upon said anchor-disk, a lock-disk seated within said head-shell and resting upon said laterally 115 extending arm of said pin-shank, said head-shell having an upwardly extending marginal flange curled over and inwardly to form a tubular bead adapted to engage said lock-disk to retain the same in place, an ornament element seated upon the upper surface of said lock-disk, and means connected with said bead for engaging and retaining said ornament element in place.

5. In an article of the kind described, a 125 head-shell closed at its bottom end and provided with a central perforation, an anchor-disk seated within said head-shell, said anchor-disk having a central perforation, a pin-shank extending downwardly through 130

5 said perforations of said anchor-disk and the bottom of said head-shell, a laterally extending arm connected with the upper end of said pin-shank and resting upon said anchor-disk, a lock-disk seated within said head-shell and resting upon said laterally extending arm of said pin-shank, said head-shell having an upwardly extending marginal flange curled over and inwardly to
10 form a tubular bead adapted to engage said lock-disk to retain the same in place, an ornament element seated upon the upper surface of said lock-disk, and means connected with said bead for engaging and retaining

said ornament element in place, comprising 15 a series of spaced transverse and radially disposed depressed grooves, and inwardly extending gripping projections forced out from the side of said bead at the inner end of said groove adapted to engage said ornament element.

In testimony that I claim the invention set forth above I have hereunto set my hand this 22nd day of January 1916.

CHARLES WHITELEY.
